UNITED STATES PATENT OFFICE

MAXIMILIAN STANISLAW WEBER, OF CHICAGO, ILLINOIS

DESIGN FOR A GRASP BAR

Application filed May 15, 1929. Serial No. 31,240. Term of patent 14 years.

To all whom it may concern:

Be it known that I, MAXIMILIAN STANISLAW WEBER, a citizen of the United States, residing at Chicago, in the county of Cook and State of Illinois, have invented a new, original, and ornamental Design for Grasp Bar, of which the following is a specification, reference being had to the accompanying drawing, forming a part thereof.

I claim:

The ornamental design for a grasp bar as shown.

MAXIMILIAN STANISLAW WEBER.
